[57] CLAIM

The ornamental design for a modular storage system, as shown and described.

DESCRIPTION

FIG. 1 is a top plan view of the modular storage system of the present invention;

FIG. 2 is a front elevational view thereof;

FIG. 3 is a left side elevational view thereof;

FIG. 4 is a right side elevational view thereof;

FIG. 5 is a rear elevational view thereof; and,

FIG. 6 is a bottom plan view thereof.
